(57) **CLAIM**

The ornamental design for a walkie-talkie, as shown and described.

DESCRIPTION

1. Walkie-talkie

1.1 : Front

1.2 : Back

1.3 : Left

1.4 : Right

1.5 : Top

1.6 : Bottom

1.7 : Perspective

1.1 is a front elevation view of a walkie-talkie showing our new design; 1.2 is a back elevation view thereof; 1.3 is a left side elevation view thereof; 1.4 is a right side elevation view thereof; 1.5 is a top plan view thereof; 1.6 is a bottom plan view thereof; and 1.7 is a perspective view thereof.

The broken lines in Figures 1.1-1.7 depict portions of the walkie-talkie that form no part of the claimed design.

1 Claim, 7 Drawing Sheets
